PISTON CLEANING APPARATUS

Carl A. Stine, Van Nuys, Calif., assignor to Turco Products, Inc., Los Angeles, Calif., a corporation of California.

Application October 12, 1943, Serial No. 505,961

11 Claims. (Cl. 15—21)

My invention has to do with piston cleaning apparatus.

As is well known, the pistons of internal combustion engines become coated with carbonaceous deposits which, unless removed, seriously impair efficient operation of the engine. Heretofore such deposits have been removed by scraping or by immersing the piston in a solvent solution. In either case, however, the operation has required a considerable time element during which the vehicle or the like driven by the engine must remain idle.

As disclosed in my copending application Serial No. 474,312, filed February 1, 1943 (Pat. No. 2,376,945, issued May 29, 1945), I have been able to considerably speed up and increase the efficiency of carbon-removing operations by applying rotary brushes to the pistons while they are immersed in a solvent solution. In my said copending application I employ rotary brushes disposed in a tank containing the solvent solution. My present apparatus embodies improvements over that described in my copending application and it is among its objects to provide in such a cleaning apparatus improved means for removing and applying the pistons, and for inspecting them during the cleaning operation, without the necessity of the operator placing his hands in the solvent solution and without the necessity of stopping the driving motor.

Another object of the present invention is to provide improved means of adjusting the brushing pressure on the pistons, for detachably holding the pistons in position for cleaning and for rotating the pistons and brushes.

Another object is to provide an improved brush arrangement.

My invention has still further advantages and objects and how those as well as the hereinabove enumerated objects are achieved will be best understood from the following detailed explanation of one form of apparatus in which the invention may be carried out. For the purposes of the following description I shall refer to the accompanying drawings, in which:

Fig. 1 is a longitudinal section taken on line 1—1 of Fig. 3;

Fig. 2 is a section on line 2—2 of Fig. 1, but showing the cover lid in open position;

Fig. 3 is a section on line 3—3 of Fig. 2, but with the pistons removed;

Fig. 4 is a section on line 4—4 of Fig. 2;

Fig. 5 is an end elevation;

Fig. 6 is a fragmentary section;

Fig. 7 is a fragmentary section showing one of the piston-holding blocks; and

Fig. 8 is a fragmentary vertical sectional view of a modified form of apparatus.

In the drawings, I show a rectangular tank 5 which may or may not have supporting legs, not shown, and having a cover lid 8 hinged at 6 (Fig. 2) to a flange 5a disposed longitudinally along the top edge of the tank.

While my apparatus may be adapted to clean any desired number of pistons at once, I show an adaptation for cleaning six pistons P, disposed in two parallel rows of three pistons each.

Secured to the floor of the tank there are six tables 10, the tables being arranged in two parallel rows of three tables each. Two pairs of slide bars 12 extend transversely through and are slideable with respect to the tables, the tables providing tubular slideways 10a to pass the bars. Bearing members 16 are secured, as by welding, between each pair of slide bars 12. A brush-operating shaft 17 is journaled in each bearing 16, a sprocket wheel 18 being secured on the bottom end and a radial brush 19 being secured on the top end of each shaft 17. The inner or free ends of the bars 12 are slidably disposed in openings in posts 20, which posts are secured to the floor of the tank.

To operate the respective pairs of slide bars 12 I provide a pair of levers 22, each of the levers being pivotally secured at its lower end to one pair of the bars 12 and being fulcrumed by means of a bracket 23 secured to the end wall of the tank. A ratchet mechanism (Fig. 6) consisting of a rack 25 and pawl 26 is provided to releasably retain each lever in any adjusted position. The rack 25 is secured to a top plate 24 carried by the tank, the plate presenting a pair of slots 24a to pass the respective levers 22.

Atop each table 10 I resiliently mount a stationary brush 11 by means of an upwardly bowed leaf spring 27. A bearing member 30 is secured to the tank floor adjacent one end of the tank in a plane between the rows of tables 10, which bearing rotatably carries a sprocket 31, and a continuous chain belt 34 is disposed in engagement with the sprockets 18 and 31 in a manner to drive adjacent sprockets 18 of each row in opposite directions.

A driven shaft 35 is secured in sprocket 31 and in a bevel gear 36, the shaft being journaled in a bracket 37 secured to the end wall of the tank. A drive shaft 40, which may be operatively connected to an electric motor or other source of power, not shown, extends through the end wall of the tank and has secured thereon a beveled gear 41 which meshes

with gear 36. The top end of shaft 35 carries a collar 42 which has upwardly opening recesses 42a providing one member of a clutch, as will be described.

A plurality of bearing members 50, six in number, are disposed in two parallel rows of three each, are secured to the cover lid 8 and each journals a shaft 52 whose lower end resiliently fits in the socket 53a of a yoke 53. The yoke is longitudinally slotted at 53b to permit sliding movement of a cross pin 52a carried by shaft 52, and a coil spring 51 is interposed between the lower end of the shaft and the bottom of the socket. The yoke engages over a piston-retaining block 54 to which it is secured as by a cross pin 55. A sprocket wheel 56 is secured on each shaft 52, each shaft 52 being positioned to overhang one of the tables 10 when the table is down (Fig. 1). Each piston-retaining block 54 is provided with a transverse opening 54a to receive a retaining pin 57, which pin passes through the opening in the block and the wrist pin holes conventionally provided in the piston, so as to hold the piston against longitudinal escape from the block. Each pin 57 may be secured against longitudinal movement in its opening 54a by a diagonal pin 50a (Fig. 7). Each pin 50a is yieldably urged inwardly by a spring 58, the inner end of the pin engaging in an annular groove 59 in a pin 57.

Also secured to the cover lid so as to be coaxial with collar 42 when the lid is down (Fig. 1) there is a bearing 60 journaling a shaft 61, a sprocket 62 being secured on the shaft. The lower end of the shaft 61 carries a collar 63 which presents teeth 63a engaging in the recesses 42a thus providing the other element of the clutch hereinabove mentioned. A continuous chain belt 65 engages with the teeth of sprockets 62 and 56, being so disposed around the latter sprockets as to rotate adjacent sprockets of each row in opposite directions. Collars 70 are secured on the projecting top ends of the respective shafts 52, 61, to prevent inward longitudinal movement of the shafts.

A trough member 75 is provided around the top edge of the tank and a depending flange 76 is provided on the cover lid. This trough is normally kept filled with liquid to provide a seal between the cover lid and tank to prevent escape of vapors. In practice the tank is filled with a carbon solvent, many of which solvents are well known in the art, to approximately the liquid level L (Fig. 1).

For raising and lowering the cover lid 8 I provide means which will now be described. A pair of posts 80 are supported on brackets 81 carried by the tank, and atop each post a sheave 82 is rotatably carried by a bracket 84. A shaft 85 is journalled in the posts 80 and a pair of drums 87 are secured on the shafts. A pair of cables 88 are windable at one end about the drums and are secured at their other ends to the cover lid so that rotation of shaft 85 and drums 87 wind the cables to lift the lid. Alternate means are provided for rotating shaft 85—one means being (Fig. 5) manual and including a sprocket 90 secured on the shaft, a sprocket 91 secured on a crank 92 journalled in the tank end wall and a chain belt 93. A ratchet 94 and pawl 95 serve to lock the sprocket 91 against reverse rotation.

A means for lifting the lid by the motor used to drive the cleaning apparatus is also provided and will now be described. It includes a shaft 100 rotatably carried by brackets 101 secured to

an end wall, a bevel gear 102 meshing with gear 41 and one element 103a of a clutch. Another coaxial shaft 105 carrying a clutch element 105a is longitudinally slidably and rotatably supported by an end wall bracket 107 and extends through a side wall of the tank, carrying on its outer end a bevel gear 108 adapted to mesh with a bevel gear 108a (Fig. 2) on the shaft 85. A lever 110 is pivoted at its lower end on a bracket 81 and has a link 111 so connected to shaft 105 as to slide the shaft longitudinally but allow rotation of the shaft. A spring 115 urges the lever outwardly to disengage the clutch elements 103a and 105a.

Each brush 19 has a relatively large diameter base portion 19a and a relatively smaller diameter top portion 19b which portions intersect each other in a curved portion 19c. Thus the beveled ends of the pistons are reached by brush portion 19a while portion 19b engages the sides and ring grooves of the piston.

For guiding and taking up slack in the belt 34 I provide an idler sprocket 120 rotatably mounted on an arm 121 pivotally connected at its other end to a support secured to the tank floor. A transverse slot 122 is provided in the arm through which an adjusting screw 123 extends. Another idler sprocket 125 is rotatably carried by an arm 126 whose other end is adjustably pivotally secured by means of an adjusting screw 127 to a slotted bar 128 carried by support 129 secured to the floor.

In operation the tank is filled to the liquid level L with a carbon solvent and the pistons P are placed on the perspective retaining blocks 54 while the lid is in the raised position of Fig. 2. The lid is then lowered which causes the pistons P to be radially engaged by the brushes 19 and to have their lower end resiliently engaged by the stationary brushes 11. Also, when the lid is lower, the toothed lower end of the shaft 61 is engaged with the recessed top end of collar 42; so that rotation of shaft 40 causes simultaneous rotation of belts 34, 65 when said clutch is engaged. The levers 22 may be manually operated to slide the brushes 19 towards or away from the pistons to compensate for pistons of varying diameters and to increase or decrease the brushing pressure when desired. During the operation the brushes, belts and sprocket wheels also function to agitate the solvent solution and the brushes rapidly remove any loosened deposit to enable the solvent continuously to have access to a fresh surface. I find that by my apparatus pistons may be cleaned in a few minutes which heretofore have required several hours to clean by known apparatus.

When it is desired to inspect the pistons or to remove them, the cover lid is raised, which disengages shaft 61 from the driving mechanism so that the pistons cease to rotate and may be handled and inspected without the operator having to place his hands in the solvent as well as without having to stop the driving motor.

In Fig. 8 I show an adaptation of my invention for the cleaning of engine cylinders and the like. Here the numeral 5b denotes a bottom wall of a tank such as tank 5 hereinabove described, and 8a designates the hinged top wall. A bearing 135 is secured to the bottom wall, within which bearing the lower end of a shaft 136 is journalled. An adapter 137 is secured on the top end of shaft 136, this adapter presenting an upwardly opening socket 138 of squared cross section to receive the squared lower end of the brush shaft 139, which

carries at its upper end a brush 140. A sprocket wheel 141 is secured on the shaft 136, which sprocket is driven by a chain belt 34a from a drive mechanism such as hereinabove described. A base member 145 rotatably fits shaft 136, the base member having a spherical top surface 145a to accommodate cylinders C of varying diameters.

A bearing member 150 is secured to the top wall to journal a shaft 151 carrying a sprocket wheel 152 driven by a chain belt 65a from a driving mechanism such as before described. A work-retaining yoke 155 is secured to the lower end of the shaft and carries at the lower ends of its respective arms retaining plates 156 which are adapted to be secured as by cap screws 157 to the cylinder head portion C'. The brush 140 is rotated against the inner end of the cylinder while the cylinder is rotated in opposite direction by the shaft 151. Since the cylinder is thus rotated and brushed while submerged in the cleaning solvent within the tank or casing, the solvent may enter the cylinder through the ports 160 conventionally provided in cylinder heads. Lifting of the lid or top wall, in the manner before described, removes the cylinder from the solvent solution for inspection or removal.

While I have resorted to considerable detail for the purpose of making my invention understood, I wish it understood that within its broader scope, as defined by the appended claims, various modifications and adaptations may be made without departing from the spirit of the invention.

I claim:

1. Cleaning apparatus comprising, in combination, a solvent-containing tank having a cover lid, a work-holding member rotatably supported by the cover lid, a brush rotatably carried in the lower part of the tank for brushing engagement with work held on the work-holding member, and means for rotating the work-holding member and the brush, said cover lid being hingedly mounted on the tank for swinging movement relative thereto whereby the work may be withdrawn from the tank by virtue of swinging the cover lid upwardly therefrom.

2. Cleaning apparatus comprising, in combination, a solvent-containing tank having a cover lid swingably mounted thereon, a work-holding member rotatably supported by the cover lid, a brush rotatably carried in the lower part of the tank for brushing engagement with work held on the work-holding member, driven means for rotating the work-holding member, driven means for rotating the brush, drive means normally operatively connected to said driven means, and a clutch between the drive means and the driven means for rotating the work-holding member, said clutch member being disengageable by virtue of swinging the cover lid relative to the tank.

3. The apparatus of claim 2 which includes hoist means for swinging the cover lid upwardly from the tank and wherein the hoist means is operatively connected to and actuated by the drive means.

4. Cleaning apparatus comprising, in combination, a solvent-containing tank having a cover lid movably mounted for opening and closing the tank, a work holder rotatably journalled on the lid, a sprocket wheel secured on the work holder, a radial brush mounted for rotation in the lower part of the tank, a sprocket wheel secured to the brush, a first driven sprocket rotatably journalled on the lid, a belt operatively connecting the sprocket with the sprocket wheel secured on the work holder, a second driven sprocket, a belt op-

eratively connecting the second driven sprocket with the sprocket wheel on the brush, means for operating the belts and a clutch interposed between the last-named means and the first driven sprocket, said clutch being disengageable by virtue of movement of the lid to open position.

5. Cleaning apparatus comprising, in combination, a solvent-containing tank having a cover lid movably mounted for opening and closing the tank, a brush non-rotatably supported in the bottom portion of the tank, a work holder rotatably carried by the lid over said brush whereby work held by the holder engages said brush, a radial brush supported in the bottom portion of the tank for rotation about an axis laterally offset from the axis of rotation of the work holder whereby to radially engage work held by the work holder, means for moving the radial brush with respect to the axis of rotation of the holder, and means for driving the holder and rotary brush.

6. Cleaning apparatus comprising, in combination, a solvent-containing tank having a cover lid movably mounted for opening and closing the tank, a work holder rotatably carried by the lid, said holder being adapted to carry work to be cleaned, a radial brush rotatably journalled in the lower part of the tank, said brush being shaped to conform to the surface of the work to be cleaned and being radially engageable thereagainst, and means for simultaneously rotating the work holder and brush.

7. Cleaning apparatus comprising, in combination, a solvent-containing tank having a cover lid movably mounted for opening and closing the tank, laterally spaced, aligned work holders rotatably carried by the cover lid whereby to be moved into and out of the tank by virtue of closing and opening movement of the lid, laterally spaced aligned radial brush elements rotatably journalled in the lower portion of the tank about axes laterally offset from the axes of the work holders whereby to laterally engage work carried by the work holders, means for laterally moving the brush element relative to the axes of the work holders and rotative means operatively connected to the work holders and brush elements.

8. Cleaning apparatus comprising, in combination, a solvent-containing tank having a cover lid swingably mounted thereon, a plurality of tables supported in alignment above the floor of the tank, a brush resiliently and non-rotatably mounted on each of the tables, a pair of parallel, horizontally spaced rods longitudinally slidably mounted in the tables, bearings secured between the rods between the respective tables whereby to be laterally movable with respect to the tables, radial brushes one journalled in each of the bearings, work holders disposed in the tank and rotatably carried by the lid in position to overhang the respective tables, said work holders being removable from the tank by virtue of lifting the lid, and drive means for operating the radial brushes and work holders.

9. Cleaning apparatus comprising, in combination, a solvent-containing tank having a cover lid swingably mounted thereon, a plurality of tables supported in alignment above the floor of the tank, a brush resiliently and non-rotatably mounted on each of the tables, a pair of parallel, horizontally spaced rods longitudinally slidably mounted in the tables, bearings secured between the rods between the respective tables whereby to be laterally movable with respect to the tables, radial brushes one journalled in each of the bearings, work holders disposed in the tank and ro-

tatably carried by the lid in position to overhang the respective tables, said work holders being removable from the tank by virtue of lifting the lid, drive means operatively connected to the radial brushes and work holders, and clutch means between the drive means and work holders, said clutch means being disengageable by virtue of lifting of the lid.

10. Apparatus comprising, in combination, a casing, a radial work-engaging brush rotatably mounted in the casing, a work holder rotatably mounted in the casing and means for rotating the brush and work holder, said work holder consisting of a yoke, a block secured to the yoke, a transverse opening through the block, a cross pin disposed in the opening, an annular groove in

the cross pin, a diagonal bore in the block communicating with the opening and a pin resiliently mounted in the bore and having its inner end engageable in the groove.

11. Cleaning apparatus comprising, in combination, a solvent-containing tank having a cover lid swingably mounted thereon, a shaft rotatably carried by the lid and presenting means for detachably holding a cylindric article to be cleaned, 10 a shaft rotatably mounted in the lower part of the tank coaxial with the first-mentioned shaft, a brush secured on the latter shaft in position to extend into said cylindric article carried by the work holder, and means for simultaneously rotating the shafts in opposite directions.

CARL A. STINE.
